UNITED STATES PATENT OFFICE.

THOMAS W. DOWLING, OF DETROIT, MICHIGAN.

WASH-BOARD.

SPECIFICATION forming part of Letters Patent No. 360,210, dated March 29, 1887.

Application filed December 23, 1886. Serial No. 222,395. (No model.)

To all whom it may concern:

Be it known that I, THOMAS W. DOWLING, of Detroit, in the county of Wayne and State of Michigan, have invented new and useful Improvements in Wash-Boards; and I do hereby declare that the following is a full, clear, and exact description thereof, reference being had to the accompanying drawings, which form a part of this specification.

This invention relates to certain new and useful improvements in wash-boards; and the invention consists in providing the same with a guard at its upper end, that may be set to incline at a certain angle to either face of the board and retained in place without the intervention of springs, as more fully hereinafter described and claimed.

Figure 1 is a perspective view of a wash-board, showing my improvement. Fig. 2 is a vertical section of the same, showing the guard and its means of attachment to the wash-board.

In the accompanying drawings, which form a part of this specification, A represents the standards, B the rubber, and C the soap-board, all of the usual construction of wash-boards, except that there is no top rail upon the upper end of and connecting the side standards, which latter project far enough above the upper edge of the soap-board to have suitable holes, a, bored therein to form bearings, in which the ends of the rock-shaft D are properly journaled. A channel, b, is formed lon-

gitudinally in this shaft, such channel extending nearly or quite the whole length thereof between the bearings or journals upon its ends. 35

E is the guard, it being a thin piece of board, or sheet metal, if preferred, one edge of which is secured in such channel. The shaft between the standards is of two diameters in 40 cross-section, as shown in Fig. 2, the smaller being the shaft proper, while the larger forms a saddle carrying the guard-board, and has shoulders c, which limit the rotation of the shaft, as it is rocked in either direction, by 45 striking the upper edge of the guard, and thereby holding such guard at the proper angle to perform its functions.

What I claim as my invention is—

The wash-board described, consisting of the 50 standards A, double-faced rubber B, soap-board C above said rubber, the rock-shaft D, journaled in the upper ends of said standards and provided with longitudinal channel b, guard E, having one edge secured in said channel, the said shaft being formed of two different diameters, as shown and described, to form shoulders c, designed to engage the upper edge of the soap-board to limit the rotation of the shaft in either direction, substantially as set 55 forth. 60

THOS. W. DOWLING.
